UNITED STATES PATENT OFFICE.

HARRY E. ASBURY, OF PHILADELPHIA, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

SAD-IRON.

No. 895,327.

Specification of Letters Patent.

Patented Aug. 4, 1908.

Application filed February 27, 1905. Serial No. 247,577.

To all whom it may concern:

Be it known that I, HARRY E. ASBURY, a citizen of the United States, residing in Philadelphia, Pennsylvania, have invented certain 5 Improvements in Sad-Irons, of which the following is a specification.

My invention relates to certain improvements in the sad iron for which application for patent was filed by me on July 16th, 10 1904, under Serial Number 216,833.

The main object of my present invention is to strengthen the cross piece of the cap of the sad iron so that it will not be bent in testing and in use and a further object is to close 15 the opening under the bar.

In the accompanying drawing, Figure 1, is a plan view of my improved sad iron cap; Fig. 2, is an inverted plan view, with the protector removed; Fig. 3, is a longitudinal sectional view on the line 3—3, Fig. 1; Fig. 4, is a transverse sectional view on the line 4—4, Fig. 1; and Fig. 5, is a view of the protector.

A is the body of the sad iron; this body may be of any suitable shape.

25 B is a sheet metal cap having a flange b which overlaps the edge of the body portion of the sad iron and fits snugly thereto. This cap is secured to the body portion A by screws passing through flanged openings a in 30 the cap. Extending across the cap is a central rib d and on each side of this rib are openings b' for the passage of the clamping jaws of the handle.

In the application above alluded to the 35 cross bar was made hollow and was formed by using a portion of the metal cut out to form the openings and bending these portions under the bar, so as to form a suitable grip for the jaws of the handle.

40 After the caps are made they are tested and subjected to rather rough usage and when the irons are in use considerable strain is placed upon this cross bar and as the cross bar must be of an even diameter throughout, 45 so that the grip of the handle will accurately fit the cap. I have provided means by which it will be impossible to distort this cross bar either during testing or when the iron is in actual use. To accomplish this I place a bar 50 D between the two lips d' of the rib d before the lips are bent into position and when this bar is in position the lips are bent over the bar, as clearly shown in Fig. 2, and in order to prevent the bar moving longitudinally I

form slight projections e, e in the plate at 55 each end of the bar during the final pressing of the plate, consequently the bar is rigidly held between the lips of the rib and the rib must necessarily be at all times of the same diameter. The bar takes the entire strain 60 and prevents any distortion of the cross rib.

It will be understood that my invention is particularly adapted to struck up sheet steel sad iron caps which are made very light.

In order to close the opening under the 65 cap I provide a cup shaped protector I, as clearly shown in the detached view Fig. 5. This protector has a flange i which is notched at each end i'.

On the cap B are two lips e' which are 70 struck up from the body of the cap and are bent down so as to extend through the notches i' of the protector, the lips are then bent in against the protector so as to firmly attach it to the cap. Thus when the cap is 75 applied to the body of the sad iron the protector covers the material with which the body of the sad iron is filled, making a neat appearance.

I claim as my invention:

1. A sad iron cap having a transverse rib, with openings at each side, lips formed by a portion of the metal cut to form the openings and a bar mounted under the rib and secured thereto by bending the lips around the bar, 85 substantially as described.

2. A sad iron cap having a transverse rib with depending lips, a bar transversely arranged in respect to the cap and held to the rib by the lips, and projections on the cap at 90 each end of the bar to prevent the bar from moving longitudinally, substantially as described.

3. A struck up sheet metal cap for a sad iron having a central transverse rib with 95 openings at each side of the rib, lips formed by a portion of the metal cut from the openings, and a bar mounted under the rib and secured thereto by bending the lips around the bar, with projections struck up from the 100 body of the cap and situated at each end of the bar so as to prevent it from moving longitudinally, substantially as described.

4. A cap for a sad iron having openings for the insertion of the jaws of the handle, a 105 cup shaped protector mounted under the cap, said protector having a flange, the flange being notched at each end of the pro-

tector, lips bent down from the body of the cap and extending through the notched portions of the protector and bearing against the under side of the same, holding said protector against the under side of the cap, substantially as described.

In testimony whereof, I have signed my

name to this specification, in the presence of two subscribing witnesses.

HARRY E. ASBURY.
